UNITED STATES PATENT OFFICE.

GEORGE HOGG, OF NEW YORK, N. Y.

CAR-VENTILATOR.

SPECIFICATION forming part of Letters Patent No. 447,071, dated February 24, 1891.

Application filed June 12, 1890. Serial No. 355,168. (No model.)

To all whom it may concern:

Be it known that I, GEORGE HOGG, of the city, county, and State of New York, a citizen of the United States, have invented certain new and useful Improvements in Car-Ventilators, of which the following is a specification.

This invention relates to an improved car-ventilator of that class in which the air in the car is exhausted by creating a partial vacuum in an ejector-like structure in the top of the car, through which ejector the air is forced by the motion of the car.

In the accompanying drawings, Figure 1 represents a side elevation of a railway-car, showing the position of my improved car-ventilators. Fig. 2 is a vertical transverse section of the upper part of the car, drawn on a larger scale, so as to show the ventilators in end view and their transverse connecting-tube in side view. Figs. 3 and 4 are vertical longitudinal sections of the ventilators, showing two different constructions of the same. Figs. 5 and 6 are vertical transverse sections of the ventilators, respectively on line 3 3, Fig. 3, and line 4 4, Fig. 4.

Similar letters of reference indicate corresponding parts.

Referring to the drawings, A represents my improved car-ventilators, of which one is arranged at each corner of the car above the roof of the same, as shown in Fig. 1. Each ventilator A is constructed of a horizontal ejector a, having enlarged or trumpet-shaped ends a', which are covered by conically-shaped screens a², by which dust and cinders are prevented from entering into the ejector. The horizontal ejector-tube a is provided with an opening a³ in its bottom part and with a flange a⁴ extending around said opening, said flange forming a seat by which the ejector a rests on the upper end of a vertical suction-tube B, that passes through the roof of the car to the inside of the same and that is firmly attached to the roof. The bottom of the suction-tube B is connected by a drain-pipe b, which passes through the side wall of the car to the outside of the same, so as to conduct off any water which might get through the ejector a into the suction-pipe B. Through the center of the bottom of the suction-tube B passes a spindle d, the upper end of which

is attached to a socket d', that is supported on arms below the bottom opening a³ of the ejector-tube a. The lower end of the spindle d outside of the bottom of the vertical tube B is pivoted to two hand-levers d² d², by which the horizontal ejector-tube a can be rigidly locked to the suction-tube when the levers d² d² are pressed together or released from the same, so as to turn freely on the suction-tube B by moving the levers apart from each other, in which position the levers also serve for turning the ejector-tube a through an angle of one hundred and eighty degrees, so as to adjust it according to the direction in which the car is moved. After the proper position of the horizontal ejector-tube a is established it is locked firmly to the suction-tube B by pressing the levers d² d² together, the upper ends of the same above the pivot-connection with the spindle b acting in the nature of cams on the bottom of the suction-tube for rigidly holding the ejector-tube a in position on the suction-tube B. In the horizontal ejector-tube a is arranged either a curved hood h or a conical nozzle n, that extends over the bottom opening a³ of the ejector-tube a, so that the latter serves in the nature of an ejector when the air is forced by the motion of the car with considerable velocity through the ejector-tube a, creating thereby a partial vacuum in the suction-tube B, by which the vitiated and warm air is drawn out of the top part of the car and forced to the outside of the same. The lower ends of the suction-tubes B of the two ventilators A at each end of the car are connected by a transverse tube C, which extends across the top part of the car, as shown in Fig. 2. The transverse tube C is perforated for the free egress or ingress of the air and provided at both ends, near its connection with the suction-tubes B, with damper-like valves f, which are set by means of levers f' into open or closed position whenever it is desired to connect one or both ventilators with the transverse tube C or disconnect it therefrom. At the center of the transverse tube C is arranged a partition g, which divides the transverse tube C into two halves, one half communicating with the ventilator A at one side and the other half with the ventilator at the opposite side thereof.

In using my improved car-ventilator I pre-

fer to use a pair of ventilators at the front end of the car for the purpose of introducing fresh air into the car, while another pair of ventilators is arranged at the rear end of the car 5 for drawing out the warm and vitiated air and conducting it to the outside. For this purpose it is necessary to turn the horizontal ejector-tube *a* of the front ventilators on the suction-tubes *B* in such a position that the nozzles *n* 10 or hoods *h* are located in the direction in which the car is moving, so that the air that passes in through the screen at the end of the ejector-tube *a* is forced through the nozzles or hoods and the suction-tubes *B* into the transverse 15 tube *C* and distributed through the perforations of the latter to the interior of the car. The ventilators at the rear end of the car are adjusted for suction, their nozzles or hoods being located in the direction of the air-current 20 that passes through the ventilators, so as to produce a partial vacuum and exhaust thereby the air from the top part of the car. In this manner the ventilators arranged at the front and rear ends of the car act together, one introducing fresh air at the front end into the 25 car, while the other exhausts the vitiated air at the rear end from the car. By the perforated transverse distributing-tubes the ventilation produced by the change of air is almost imperceptibly accomplished, so as not to annoy the passengers in the car. As long as the car is in motion a continuous ventilating action takes place, which is increased according to the speed at which the car is moved. 30 When the car is moved in the opposite direction, the positions of the ventilators are changed by the mechanism before de-

scribed in such a manner that the ventilators at the front end that were before at the rear end of the car are changed, so as to conduct 40 the air to the inside of the car, while the ventilators at the rear end of the car are adjusted so as to produce a suction action and establish thereby the ventilation through the car. If desired, the ventilators at both ends of the car 45 can be set for suction, or both for the introduction of fresh air.

My improved ventilator can be applied at comparatively small expense to passenger and other cars, and can also be used as a single 50 ventilator without the transverse perforated tube for the ventilation of water-closets, smoking-rooms, &c., or at the bottom of the cars.

Having thus described my invention, I claim as new and desire to secure by Letters Patent—

The combination of a vertical air-tube, a horizontal ejector-tube mounted on the upper end of said vertical air-tube and adapted to swivel thereon, said ejector-tube having flaring mouths at its opposite ends, a jet-tube or hood and a side opening opposite said vertical tube, a spindle passing through said vertical tube and connected to the ejector-tube, and cam-levers pivoted to the lower end of the 65 spindle for turning and locking the ejector-tube.

In testimony that I claim the foregoing as my invention I have signed my name in presence of two subscribing witnesses.

GEORGE HOGG.
